WILLIAM J. LUSK, OF FENTONVILLE, MICHIGAN.

Design No. 2,863, dated January 28, 1868.

DESIGN FOR A FRAME.

The Schedule referred to in these Letters Patent and making part of the same.

TO ALL WHOM IT MAY CONCERN:

Be it known that I, WILLIAM J. LUSK, of Fentonville, in the county of Genesee, and State of Michigan, have invented a new and ornamental Design for an Advertising-Frame; and I declare that the said design is correctly represented in the accompanying drawing, which is hereby made a part of this specification.

The frame consists of exterior bars, A A, and interior bars or partitions, B B. The outer spaces C C C are for business-cards or advertisements, either written or printed. The space D is occupied by a mirror, and the space E by a time-piece, F, and a thermometer, G, beside affording room for a special advertisement or notice of any kind.

I claim, and desire to secure by Letters Patent—

The design for an advertising-frame, substantially as represented in the accompanying drawings.
